UNITED STATES PATENT OFFICE.

BENJAMIN HIRSCHHORN, OF NEW YORK, N. Y., ASSIGNOR, BY MESNE ASSIGNMENTS, TO MILLIE PATENT HOLDING CO. INC., OF NEW YORK, N. Y., A CORPORATION OF NEW YORK.

METHOD OF MANUFACTURING TEA CARTRIDGES.

Application filed February 3, 1923. Serial No. 616,772.

To all whom it may concern:

Be it known that I, BENJAMIN HIRSCHHORN, a citizen of the United States, and resident of the city of New York, in the 5 county of Bronx and State of New York, have invented certain new and useful Improvements in Methods of Manufacturing Tea Cartridges, of which the following is a specification.

10 The present invention relates to a method of making tea cartridges, that is to say devices for percolating or extracting the flavor from tea-leaves or coffee.

One type of these cartridges, described in 15 U. S. Letters Patent No. 1,310,796, granted to me on July 22, 1919, comprises a bag of textile fabric having its mouth drawn into folds, the mouth of the bag being closed by a metal strip, in the form of a ring, which 20 engages and compresses the folds, in combination with a suspending string which is attached to said bag by said strip. In making these cartridges, obviously, a bag must be first formed from a piece of textile fabric 25 on a sewing machine.

The main object of the present invention is to provide a method of forming tea cartridges, which does away with the sewing operation, thereby greatly reducing the 30 cost of manufacture.

Generally speaking, the method consists in shaping a piece of fabric so as to form a bag-like container, charging said container with tea-leaves or coffee, puckering a 35 the mouth of the container, and placing a metal strip around the puckered mouth-portion so as to encircle and compress the same and thereby for closing the mouth of the container.

40 One of the many possible apparatuses for carrying out the method is illustrated in the accompanying drawings, in which:—

Figure 1 is a plan view of a piece of fabric, of which the container of the cartridge is formed; Fig. 2 is a vertical central section taken through the apparatus and fabric piece, showing one of the steps of the method; Fig. 3 is a similar section showing a further step; Fig. 4 is a plan view of the means for puckering the mouth portion of the container; Fig. 5 is an elevation of a completed tea-cartridge before the trimming operation; and Fig. 6 is a plan view of one of the co-operating dies

which serve to hold the fabric piece during 55 the shaping operation.

In producing a cartridge, first a piece 10 of open-mesh textile fabric, preferably of square configuration, is cut from a strip. This fabric piece is placed upon a die 11, 60 having the same configuration as the said fabric piece, it being provided with a central opening 12, registering with a hole 13 in a table 14. The die is placed into a mortise 15 in the table, with its exposed face 65 flush with the upper face of the table. The die is provided with radial corrugations 16 in its exposed face, said corrugations extending from the opening 12 to the edges thereof, as clearly shown in Fig. 6 of the 70 drawings. Into the hole 13 extends a plunger 17, slideable in a guide 18, below the said table. Above the die 11 and in registering position therewith is slidably arranged in guides, not shown, a similar die 75 19. This die is provided in its underface with corrugations 20, the ridges in the latter die registering with the furrows in the die 11, and the ridges in the die 11 with the furrows in the die 19. The die 19 is 80 provided with a central opening 21, in alignment with the opening 12 in the die 11. Through the openings and hole in the dies and table, respectively, a tube 22 slides, as will hereinafter appear.

85 Below the table 14 are arranged, on diametrically opposite portions of the hole 13, oppositely movable puckering dies 23, each being provided with a notch 24 (Fig. 4) in its inner end.

90 In producing a tea cartridge, the fabric piece 10 is placed onto the die 11, the plunger 17 being brought to its upper position, as shown in Fig. 2 of the drawings. The die 19 is then lowered onto the fabric piece, 95 producing uniform radial flutings in the said fabric piece around a plain portion, the latter being disposed within the registering openings 21 and 12 in the dies 19 and 11, respectively. The tube 22 is then moved 100 through the openings in the dies and the hole 13 in the table 14, forcing the plunger 17 downwards (Fig. 3), and carrying with it the fabric piece, thereby shaping the same and forming a container 25, as shown in 105 Fig. 3 of the drawings. A quantity of tea-leaves or coffee 26 (Fig. 3), sufficient for a single brewing, is then inserted through the

tube 22 into the container 25, and the said tube withdrawn, the mouth portion of the container being located within the hole 13 in the table 14. The dies 23 are then moved 5 inwards, that is to say toward the center of the hole in the table 14, puckering the mouth of the container. While these puckering dies are in their inner positions, a metal strip 27 is applied to the container, the said 10 strip being shaped to assume the form of a ring, embracing the puckered mouth portion and holding the folds under compression, to prevent escaping of the contents.

For the purpose of facilitating the handling of the cartridge, there is secured thereto a flexible means, such as a string 28, to which is attached at its free end a handle 29, for instance, of cardboard. The string 15 is secured to the cartridge by placing it 20 against the puckered mouth of the container before the ring-shaped closure is applied thereto.

The mouth of the bag may be trimmed by a knife 30 (Fig. 5) of any suitable construction.

In brewing tea or coffee with the improved device, the cartridge is taken hold of by its handle 29, and lowered into a pot, the free end of the string and handle being 30 permitted to hang over the mouth of the pot, after which its cover is put in place. The cover thus holds the outer end of the string and handle ready for further operation. Into the pot is poured a suitable 35 quantity of boiling water, either before or after the insertion of the cartridge. When

sufficient essence has been extracted from the tea-leaves or coffee within the cartridge, the pot cover is removed and the cartridge withdrawn by grasping its handle 29.

What I claim is:—

1. The method of producing a tea or coffee cartridge, which consists in, first, shaping a piece of open-mesh textile fabric into the form of a seamless bag-like container while 45 uniformly distributing the excess material into substantially vertical loose folds extending from adjacent the center of the fabric piece to the upper portion of the container, second, inserting into the container while 50 held distended the material the essence of which is to be extracted, third, puckering the mouth of said container by drawing said folds all toward the longitudinal axis of said container, and, fourth, applying a 55 closure to the mouth portion of the container in the meanwhile holding the said mouth portion clamped.

2. That step of the method of producing a tea or coffee cartridge, which consists in 60 shaping a piece of open-mesh textile fabric into the form of an open-mouthed seamless bag-like container while uniformly distributing the excess material into substantially vertical folds extending from adjacent the center of the fabric piece to the 65 upper portion of the container.

Signed at New York, in the county of New York and State of New York, this 28th day of November, A. D. 1922.

BENJAMIN HIRSCHHORN.
